United States Patent Office.

M. R. SHALTERS AND SAMUEL RAY, OF ALLIANCE, OHIO.

Letters Patent No. 75,988, dated March 24, 1868.

IMPROVEMENT IN DOUBLE-SHOVEL PLOUGHS.

The Schedule referred to in these Letters Patent and making part of the same.

TO ALL WHOM IT MAY CONCERN:

Be it known that we, M. R. SHALTERS and SAMUEL RAY, of Alliance, in the county of Stark, and in the State of Ohio, have invented certain new and useful Improvements in Double-Shovel Ploughs; and do hereby declare that the following is a full, clear, and exact description thereof, reference being had to the accompanying drawings, and to the letters of reference marked thereon.

In the annexed drawings, making part of this specification, A A represent the two handles of a shovel-plough, which bend downwards at their lower ends, as represented, and have secured to these ends the shovels B B, thus dispensing with standards or shanks, other than the handles themselves. D represents a T-shaped box, which is cast hollow. The rear end of the beam is fitted into the leg of this box, while two braces, C C, each of which has one end secured to the inside of each of the handles, pass each other through the wings of the box. A set-screw, a, serves to secure the braces C C at any desired point within the box D. G represents a tube, which is secured to one of the handles near its outer end, and H is a rod, which is passed into said tube, having one end secured to the other handle. A set-screw confines the rod to the tube, when desirable. By means of the braces C C, and the rod and tube H and G, the handles, and consequently the shovels, are set wider apart or closer together. F F represent two braces, which are slotted at one end, and are confined by a bolt to the beam E, through these slots. The other ends of these braces are secured to the handles A A. These braces are slotted, in order to accommodate themselves to the extension or contraction of the handles A.

It will readily be perceived that, by means of this arrangement and construction, a very cheap, simple, and efficient adjustable double-shovel plough is made.

What we claim as new, and desire to secure by Letters Patent, is—

1. The T-shaped box D, for forming the main frame of a double-shovel plough, substantially as herein set forth.
2. In combination with the box D, the braces C C and handles A A, substantially as and for the purpose specified.
3. The arrangement of the braces F F, C C, and the rod H and tube G, with the handles, and beam for contracting and expanding the frame, substantially as herein set forth.

In testimony that we claim the foregoing, we have hereunto set our hands, this   day of   , 1867.

M. R. SHALTERS,
SAMUEL RAY.
